LINE CASTING MACHINE

Charles W. Curle, San Francisco, Calif.

Application January 29, 1934, Serial No. 708,779

13 Claims. (Cl. 199—59)

This invention relates to improvements in line casting machines, and has particular reference to the mechanism employed for finally trimming the cast lines to exact thicknesses.

5 A further object of this invention is to produce a device which will trim the cast lines so as to make them parallel and accurate, so that they may be assembled into columns and locked into forms for printing without further manipulation.

10 Another object is to produce a device which is economical to manufacture and install upon present day equipment.

15 A still further object is to produce a device of this character which eliminates the customary trimming knives of a line casting machine.

20 Other objects and advantages will be apparent during the course of the following description:

In the accompanying drawings forming a part of this specification and in which like numerals are employed to designate like parts throughout 25 the same,

Fig. I is a front plan view of my device as the same would appear when attached to the ordinary knife block support of a line casting machine.

25 Fig. II is a side elevation of Fig. I.

Fig. III is a cross-sectional view on the line

III—III of Fig. I and on an enlarged scale.

30 Fig. IV is a cross-sectional view on the line IV—IV of Fig. I and on an enlarged scale.

Fig. V is a top plan view of the cutter head carrying slide on the same scale as Fig. I.

Fig. VI is a cross-sectional view on the line VI—VI of Fig. IV.

35 Fig. VII is a front elevation of the stationary slug guide showing the back trimming knife attached thereto, and

Fig. VIII is a top plan view of Fig. VII.

40 As is well understood in machines of this class, a line of type is cast from an assembled line of

intaglio matrices, and in some cases blank lines are cast to separate the type lines from each other, and so produce spaces between the lines. In either case, the lines or slugs as they are called, are cast in a mold which has numerous grooves

45 cut crosswise of its length, which grooves therefore produce on the slug ribs or ridges. These ribs are subsequently operated upon by shearing knives so mounted on the machine that when the slug is forced between them the knives remove the surplus metal and reduce the slug to the required thickness. These knives are usually separable and adjustable to permit slugs of varying thicknesses to be trimmed on both sides, it being understood, however, that the ribs or ridges are

50 cast upon only one side of the slug, the opposite

side of the slug being cast relatively smooth. The joint between the matrices and mold, however, is rarely close enough to prevent a slight leakage of the molten metal, and this results in a slight burr being formed parallel with the face of the slug, which it is necessary to remove to make the surface of the slug smooth and even on that side. As adjustments of the mold are made to produce thicker slugs to accommodate larger type faces, the position of the trimming knives must be likewise and correspondingly altered to trim the ribs or ridges on the slugs to make the lines of accurate thickness and also parallel from top to base and from end to end. This requires frequent alterations of the trimming 10 knives in these line casting machines which occur in practice many times every day, and has led to scores of inventions to move the knives and maintain their parallelism, but up to the time of the present invention, none has proven absolutely 15 accurate and reliable.

My invention contemplates the entire removal of the side trimming knives of such line casting machines and the substitution thereof of a rotary trimmer, or trimmers, to operate on the cast ribs of a linotype or other slug in such a manner as will produce a finished slug accurate from end to end and top to bottom. This desirable result is obtained in my invention by the new and novel manner in which the slug is presented to the trimmers, i. e., endwise, that is, in the line of its longest dimensions, instead of in the former manner, which was from face to foot, in the line of its shortest dimension. As a consequence, the slug is positively held and controlled throughout the 20 entire trimming operation, resulting in a perfectly parallel and square finish from end to end and from top to bottom, a result heretofore impossible with the type of shearing knives commonly employed in line casting machines of this class.

By trimming the back and front sides of the slug alternately, I maintain control of the slug as it passes through both trimming operations, so the operation of one trimmer does not in any manner affect the operation of the other trimmer.

Obviously, I might employ trimming mechanism other than rotary cutters, or might substitute parallel knives for trimming both back and front sides without departing from the spirit 50 or scope of my invention. Wherever in the claims or specifications, I use the term trimmers or knives, I desire it to be understood to mean either or both rotary or stationary. The essential feature in either case is that the slug be 55

passed through such trimmers endwise, i. e., lengthwise, and not as heretofore, from face to base.

In the accompanying drawings wherein for the purpose of illustration is shown a preferred embodiment of my invention, the numeral 5 designates a portion of the line casting machine and will hereinafter be termed a support. This support is to the right side of the first elevator slide and it is to this support that I secure my attachment. The numeral 6 designates a casting which is secured to the support by a screw 7 and pins 8. This casting is milled underneath so as to position the end 9 of a threaded cylindrical casting 11. The end 9 is secured to the casting 6 by a screw 12. Therefore, the casting 6 and the cylindrical casting 11 are held in fixed position relative to each other. Mounted beneath the casting 6 are guides 13 which slidably support a cutter head carrying casting 14. This casting has a guide wing 16 formed integral therewith and a bearing block 17 also formed integral therewith. A spring 18 positioned between an abutment formed upon the bottom of the casting 6 and the end of the casting 14 normally tends to push the casting away from the abutment, the purpose of which will be later seen. Mounted upon the guide wing 16 is a guide block 19 and mounted upon the bearing block is a slidable bearing 20 which is best illustrated in Fig. III. This bearing carries a rotatable cutter head 21 having cutters 22 and is driven by a pulley 23 connected to a spindle 24, the head of which abuts thrust bearings 26. The spindle is connected to the cutter head 21 in any approved manner. Slidably positioned in the cutter head is a spring-pressed plunger 27 which is normally held outwardly away from the cutter-head by a spring 30. Positioned on the bearing block and on opposite sides of the slidable bearing are supports 28 and 29 which supports slidably positioned spring-pressed guides 31 and 32, respectively, the purpose of which will be later described. By viewing Fig. I, it will be noted that the slidable bearing is adjusted in its block through the medium of wing nuts and in order to avoid confusion, numbers have been omitted as they are obvious. By again viewing Fig. IV, it will be noted that the cylindrical casting 11 is externally threaded and that a tubular nut or gauge drum is internally threaded and positioned upon the casting so that its face bears against the casting 14 at the points A (see Figs. I and V). Mounted upon the casting 6 is a gear box here shown as two castings 33 and 34. These castings are so formed as to provide a track-way 36 adjacent the guide face 37. A return track-way is shown at 38. A chain 39 is reaved over pulleys mounted at the opposite ends of the casting and adjacent the guide faces 37. This chain is driven by an intermittently driven sprocket 41 driven by a segment 42, which may be driven in any convenient manner, as for instance through a crank arm 43 connected to a pitman 44. This chain 39 has a detent 46 which extends through the slot 47 and is adapted to engage the end of the slugs for passing them through the machine as will be later described. A galley 48 of conventional form is mounted upon the casting 6 so as to receive the slugs in stacked position and to be advanced along the galley by the customary pusher arm 49.

Referring now to Figs. VII and VIII it will be noted that the face of the slug guide 37 has a knife 51 angularly disposed upon the guide face

so as to cut from the back or smooth side of the slug any slight burrs which would interfere with the perfect operation of the trimming mechanism. Referring now to Figs. I and II, it will be noted that a pivoted plate 52 is suspended in alignment with the slug to be ejected from the machine and that a plate 53 is supported by a spring 54 in a vertical position and is carried upon the guide wing 16. The ejector blade is shown at 56 about to eject a slug B to be operated upon by my machine.

The operation of my machine is as follows:—

The line casting machine is operated in the usual manner with the result that a slug is cast and ejected from the machine, the slug being shown at B in Fig. II, just as the same is being pushed forwardly by the blade 56 of the line casting machine. This slug will now pass between the upright support 5 and the spring-pressed plate 53. The reason for having this plate spring-pressed is to accommodate slugs of different thicknesses. Assuming that we are casting slugs which are to be 10 points thick, the gauge drum is turned until the pointer (see Fig. I) indicates 10 points, and assuming that this has been previously done, the slug will now encounter the pivoted member 52 which will tip the slug backwardly and cause it to fall onto the guideway between the guide 19 and the surface 37. At about this time the pitman 44 will be actuated so as to move the segment 42 and thence the sprocket 41, with the result that the chain 39 will move its detent 46 against the end of the slug and continued movement of the chain will force the slug first into engagement with the spring-pressed guide 32, thence into engagement with the spring-pressed plunger 27 in the cutter head and then into engagement with the spring-pressed guide 31 and on into the galley. While the slug is passing in front of the cutter head, it is obvious that the cutters 22 will trim from the ribbed surface of the slug the correct amount of material to make the slug the proper thickness. At the same time any burrs upon the smooth side of the slug will have been removed by the knife 51. Now assuming that it is desired to trim a slug of less thickness, the operator grasps the gauge drum and by rotating it moves the drum upon the cylindrical casting 11, thus forcing the casting 14 against the tension of the spring 18 which will move not only the guide block 19 but also the cutter head and spring-pressed guides 31 and 32 simultaneously to effect a new adjustment. When it is desired to trim a thicker slug, the direction of rotation of the gauge drum is reversed and as the drum is moved away from the casting 14 the spring 18 will function to cause the casting to follow the receding gauge drum.

Thus, it will be seen that I have produced a device which will receive the ejected slugs from a line casting machine and will deliver them to the galley correctly trimmed as to standard thickness, a feat which is not possible at the present time with the trimming knives commonly employed.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a device of the class described, in combination with a line casting machine, of slug trimming mechanism therefor, means for feeding the slugs endwise into said mechanism, said mechanism embodying means for resiliently clamping the moving slug, fixed means for trimming one side thereof, and rotatable means for trimming the opposite side thereof as it is moved through the machine.
2. In a device of the class described, in combination with a line casting machine, of slug trimming mechanism therefor adapted to alternately trim both sides of a slug as it is fed through said mechanism, means for moving said slug, and means for resiliently clamping the same during the trimming operation.
3. In a device of the class described, in combination with a line casting machine, a slug trimming mechanism therefor, means for moving a slug through said mechanism, trimming means arranged on opposite sides of said slug adapted to alternately surface both sides thereof, and means for exerting pressure upon the slug as it is moved therethrough.
4. In a device of the class described, in combination with a line casting machine, of a trimming mechanism cooperating therewith and embodying a channel through which the slug is moved, trimmers arranged in said channel to alternately operate on opposite sides of the slug, presser means for exerting pressure against the moving slug, means for moving said slug through said channel, and means for adjusting the cutting depth of one of said trimmers.
5. In a device of the class described, in combination with a line casting machine, of trimming mechanism cooperating therewith and adapted to receive the cast slug therefrom, said trimming mechanism embodying a channel or trackway, means for tilting the slug into said trackway, means for gripping and moving the slug through said trackway, trimmers arranged in opposite sides of said trackway and adapted to alternately trim both sides of the slug as it is moved along, one of said trimmers being fixed and the other being adjustable relative to the slug, and presser means for exerting pressure against said slug during the trimming operation.
6. Means for trimming slugs as received from a line casting machine comprising, a trimming mechanism cooperating therewith and positioned to receive the slugs therefrom, said means embodying means for resiliently gripping the slugs, trimmer means for alternately surfacing both sides thereof, and means for moving said slugs past said trimmers.
7. Means for trimming slugs as received from a line casting machine comprising, a trimming mechanism cooperatively associated therewith and positioned to receive the slugs therefrom, said means embodying mechanism for resiliently gripping the slugs, trimmers for surfacing both sides thereof, one of said trimmers being rotatable, and means for moving said slugs past said trimmers in an endwise direction.
8. Means for trimming slugs as received from a line casting machine comprising, a trimming mechanism cooperatively associated therewith and positioned to receive the slugs therefrom, said
- mechanism embodying a trackway having a trimmer arranged on one side and a rotary trimmer arranged on the opposite side, spring pressers arranged on one side of said trackway to engage the slugs as they pass by the trimmers, said rotary trimmer including a spring plunger adapted to engage said slugs, and means associated with said mechanism for moving said slugs through said trackway and past said trimmers.
9. Means for trimming slugs as received from a line casting machine comprising, a trimming mechanism cooperatively associated therewith and positioned to receive the slugs therefrom, said mechanism embodying a trackway having a trimmer arranged on one side and a rotary trimmer arranged on the opposite side, spring pressers arranged on one side of said trackway to engage the slugs as they pass by the trimmers, and said rotary trimmer including a spring plunger adapted to engage said slugs, means associated with said mechanism for moving said slugs through said trackway and past said trimmers, and means for rotating said rotary cutter.
10. Means for trimming slugs as received from a line casting machine comprising, a trackway including a fixed guide and an adjustable guide, gauging means cooperating with said adjustable guide for adjusting the same relative to said fixed guide, a trimmer carried by said fixed guide, and a rotary trimmer associated with said adjustable guide, a spring urged plunger carried by said rotary trimmer, and spring pressed presser elements carried thereby, whereby a slug passing through said trackway is frictionally held in contact between said guides during the trimming operation.
11. Means for trimming slugs as received from a line casting machine comprising, a trackway including a fixed guide and an adjustable guide, gauging means associated with said adjustable guide and embodying a fixed threaded element and a threaded gauge drum, means urging said adjustable guide against said gauge drum, a trimmer carried by said fixed guide and a rotary trimmer associated with said adjustable guide, and spring presser elements carried by said rotary trimmer, whereby said rotary trimmer and said adjustable guide may be adjusted to frictionally contact and hold the moving slugs as they are passed between said fixed and said rotary trimmers.
12. Means for trimming slugs fed thereto from a line casting machine comprising, a trackway for receiving said slugs, means for moving said slugs endwise throughout said trackway, trimmers arranged on opposite sides of said trackway, one of said trimmers being fixed and the other being adjustable relative to the slug, said adjustable trimmer embodying a rotary head, and presser means carried by said adjustable trimmer and adapted to frictionally engage the moving slugs during the trimming operation.
13. Means for trimming slugs fed thereto from a line casting machine comprising, a trackway for receiving said slugs, means for moving said slugs endwise throughout said trackway, trimmers arranged on opposite sides of said trackway, one of said trimmers being fixed and the other being adjustable relative to the slug.
